(57) **CLAIM**

The ornamental design for a can top with rotatable tab opening, as shown and described.

DESCRIPTION

FIG. 1 is a perspective view of a can top with rotatable tab opening in full lines with a can shown in broken lines representing environmental association matter being for illustrative purposes only and forming no part of the claimed invention.

FIG. 2 is a top plan view of the can top with rotatable tab opening.

FIG. 3 is a bottom plan view thereof; and,

FIG. 4 is a front elevational view thereof, the rear, right side, and left side elevational views being mirror images of the front view.
